CUTTER CHAIN

John A. Hayward, Claremont, N. H., assignor to
Sullivan Machinery Company, a corporation of
Massachusetts

Application November 5, 1942, Serial No. 464,588

7 Claims. (Cl. 262—33)

This invention relates to cutter chains, and more particularly has reference to improvements in a cutter bit holder for a mining machine cutter chain.

An object of the present invention is to provide an improved cutter chain. Another object is to provide a novel means for holding a cutter bit in cutting position on a chain block. A further object is to provide a novel cutter bit holder embodying separable holder parts formed with threads engageable with a threaded socket in the chain block. A still further object is to provide a novel cutter bit holder having means whereby the same may be positively adjusted with respect to the chain block to vary the gauge of the cutter bit with respect to the block. Yet another object is to provide an improved cutter bit holder having an adjustable interlocking connection with the walls of the chain block socket. Other and further objects and their resultant advantages will be apparent after the invention becomes better understood from an examination of the specification and claims in connection with the accompanying drawing, in which one application of the invention is illustrated.

In the drawing:

Fig. 1 is a side elevational view of a section of a cutter chain illustrating the improved cutter bit holding means.

Fig. 2 is a cross sectional view taken substantially on line 2—2 of Fig. 1.

Fig. 3 is a view in longitudinal vertical section taken substantially on line 3—3 of Fig. 2.

Fig. 4 is a fragmentary sectional view taken on the plane of Fig. 3, showing the cutter bit holder in side elevation.

Fig. 5 is a perspective view of the rear holder part.

Fig. 6 is a perspective view of the front holder part.

Fig. 7 is a detail sectional view taken substantially on line 7—7 of Fig. 3.

In this illustrative embodiment of the invention there is shown a cutter chain generally designated 1 adapted to travel about the margin of a conventional mining machine cutter bar. The cutter chain includes a chain block 2 pivotally connected to strap links 3, and the latter have lateral gibs 4 adapted to engage the usual cutter bar guideways.

The chain block has a lateral lug 5 formed with a socket 6 arranged at right angles to the path of travel of the cutter chain. This block socket is preferably circular in cross section (Fig. 7), and the socket walls are threaded at 7. Arranged

longitudinally of the block at the forward side of the block socket is a threaded opening 8 for receiving a conventional set screw 9. The improved bit holding means is generally designated 10 and includes a rear holder part 11 and a front holder part 12, and these holder parts are externally threaded at 13 and 14 respectively for engagement with the threaded walls of the block socket. The front and rear holder parts have outer enlarged portions 15 and 16 which cooperate to provide a generally circular head adapted to engage within a circular recess 17 at the outer end of the block socket when the holder parts are in their innermost position. The rear holder part has a forwardly facing socket 18 provided with an arcuate rear wall 19, and this socket is shaped to receive a cutter bit 20 of generally "crescent" shape in side elevation. The cutter bit has a plane front face 21 which terminates in cutting points 22 at the opposite ends of the bits. The cutter bit seats in the socket 18 of the rear holder part, and the plane front face of the bit is engaged by a rearwardly facing abutment surface 23 on the front holder part. The set screw 9 is adjustable into engagement with the front holder part in the manner shown in Fig. 3 for clamping the cutter bit firmly in cutting position on the chain block. The front holder part has a plane surface of substantial length at 24, parallel to the axis of the holder as a whole, and the lines formed by the intersection of a plane perpendicular to the holder axis with the surfaces 23 and 24 are parallel to each other, in the holder shown, so that when the set screw 9 engages the surface 24 normally, the bit will be properly faced.

When the set screw 9 is loosened, the cutter bit holder parts 11 and 12 may be concurrently rotated relative to the chain block to screw the same outwardly within the chain block socket, thereby to enable an adjustment in the gauge of the cutter bit. The changes in gauge will be determined by the lead of the screw threads 13, 14. As it is designed to have the set screw squarely engage the surface 24, it will be evident that one turn of the holder is necessary between satisfactory engagements of the screws and proper position of the bit. In any of its adjusted positions, the holder may be clamped firmly in position by the set screw. When one point of the cutter bit becomes dull, the set screw may be loosened and the holder parts unscrewed from the block socket and removed from the block. The holder parts may then be separated to enable removal of the cutter bit. The cutter bit may

then be turned end for end with respect to the holder socket, and the holder parts again placed together and screwed into proper position in the block socket. Thereafter the holder may be firmly clamped in position by the set screw. If it is desired to change the projection or gauge of the bit with respect to the block, the holder will be screwed to a different distance into the threaded socket.

As a result of this invention it will be noted that an improved cutter bit holder is provided which may be positively and to known distances adjusted inwardly and outwardly with respect to the chain block, thereby to enable a variation in the gauge of the cutter bit with respect to the block. It will be evident that by the provision of the adjustable threaded connection between the holder parts and the walls of the block socket, the possibility of inadvertent release of the bit and holder from the block is substantially reduced. The holder parts are not only relatively simple and rugged, but also relatively inexpensive in design. Other uses and advantages of the invention will be clearly apparent to those skilled in the art.

While there is in this application specifically described one form which the invention may assume in practice, it will be understood that this form of the same is shown for purposes of illustration, and that the invention may be modified and embodied in various other forms without departing from its spirit or the scope of the appended claims.

What I claim as new and desire to secure by Letters Patent is:

1. In a cutter chain, a chain block having a circular socket provided with threaded walls, and bit holding means receivable in said socket and including cooperating separable holder parts for supporting a cutter bit in cutting position on said block and separable to permit release of the cutter bit therefrom, said holder parts each having a threaded portion engageable with the socket threads and said parts being rotatable concurrently in said socket to effect adjustment of said holding means axially in said socket to vary the gauge of the cutter bit with respect to the chain block.

2. In a cutter chain, a chain block having a circular threaded socket, and bit holding means receivable in said socket and including cooperating separable holder parts adapted detachably to secure a cutter bit in cutting position on said block, said holder parts each having a threaded portion engaging the socket threads, said parts being separable to permit release of the cutter bit therefrom, and said parts being concurrently rotatable in said socket relative to said block to screw said holding means axially into and out of said block socket to vary the gauge of the cutter bit with respect to the block.

3. A bit holder having peripheral threads for predetermining its distance of reception in a chain block socket and rotatable in such a socket to vary its position axially therein, said holder comprising cooperating separable parts each having a portion of said threads formed thereon, said parts being separable to permit release of a cutter

bit therefrom, and one of said parts having a socket for the reception of a cutter bit in a predetermined position therein, and one of said parts having means formed thereon for cooperation with securing means in various positions of axial adjustment of said holder for predeterminedly positioning a cutter bit through fixing the position of said holder.

4. In combination, a threaded bit holder, a block having a threaded socket for receiving said holder and adjustable upon rotation relative to the block axially in said socket, said holder including cooperating separable parts each having a threaded portion engageable with the socket threads, said parts being separable to permit release of a cutter bit therefrom, and one of said parts having a recess for securing a cutter bit in a predetermined position therein, and said holder further having a surface on the exterior thereof whose horizontal elements bear a predetermined angular relation to the horizontal elements in the surface of a cutter bit received in said predetermined position in said holder recess, and means arranged to cooperate with said holder surface in the different adjusted positions of the holder to fix the holder in cutter supporting position on said block.

5. In a cutter chain, a chain block having a socket, rotatable bit holding means receivable in said socket and including cooperating separable bit holding elements adapted to support and hold a cutter bit in cutting position on said block, said holding elements being separable to permit release of the cutter bit therefrom, and means operative upon concurrent rotation of said holding elements of said holding means relative to said block upon an axis extending longitudinally of the block socket for axially adjusting said holding means within said socket into different bit supporting and holding positions whereby the desired gauge of the bit with respect to said block may be obtained.

6. In a cutter chain, a chain block having a socket provided with threaded walls, and rotatable bit holding means including cooperating separable bit holding elements receivable in said socket and adapted to support a cutter bit in cutting position on said block, said holding elements being separable to permit release of the cutter bit therefrom, said bit holding means having threaded portions in threaded engagement with the socket walls and adjustable upon rotation thereof axially within said socket whereby the desired projection of the bit with respect to said block may be obtained.

7. In a cutter chain, a chain block having a threaded socket, and cooperating separable bit holding elements adapted to support and hold a cutter bit in cutting position on said block, said holding elements being separable to permit release of the cutter bit therefrom, said holding elements having threaded portions in threaded engagement with said socket walls and rotatable together to adjust axially said holding elements into different predetermined positions within said socket whereby the desired gauge of the bit with respect to said block may be obtained.

JOHN A. HAYWARD.
